DEMOUNTABLE DOOR HINGE

René Vincens, Martin-Eglise, near Dieppe, France, assignor to Societe Civile de Recherches et d'Etudes Industrielles, Neuville-les-Dieppe (Seine-Maritime), France

Filed Oct. 15, 1962, Ser. No. 230,586

4 Claims. (Cl. 312—329)

This invention relates to cabinets of which the frame structure consists of metal frames made of sections of the type described and illustrated in the U.S. Patent No. 3,042,473.

The aforesaid patent also contemplates the possibility of fitting doors on a rack of this character for converting same into a cabinet, and to this end the rack receives at the four corners of its front face fittings constituting the female elements of door-hinges which are adapted to receive the pins of the door-hinges.

However, the doors thus mounted are objectionable in that in their closed position they project from the front face of the cabinet and show relatively large clearances along their outer edges, thus permitting the ingress of dust into the cabinet.

It is the essential object of the invention to provide an improved door mounting arrangement for collapsible metal cabinet according to the aforesaid patent, which is characterized in that two strips carrying the door hinge plates are secured respectively on the upper portion and on the lower portion of the front frame of the cabinet, and act as fillistered casings to these doors.

Other features of the door mounting arrangement according to this invention will be described hereinafter with reference to the accompanying drawings in which:

FIGURE 1 is a perspective view showing a cabinet equipped according to the present invention;

FIGURE 2 is an exploded view showing the elements necessary for equipping the cabinet;

FIGURE 3 is a fragmentary vertical section showing on a larger scale a door hinge according to this invention;

FIGURE 4 is a horizontal section taken upon the line IV—IV of FIG. 3;

FIGURE 5 is a part-sectional view showing the device for locking one of the door hinges; and

FIGURE 6 illustrates the fitting of a beading on a door.

To facilitate the understanding of the present invention, only the upper strip of the cabinet will be described hereinafter, but it is clear that the lower strip is of similar design.

The strip 1 consists essentially of a channel section of a length equal to the width of the cabinet and of a width permitting the straddling of the upper cross member 5 of the front frame of the cabinet.

The upper flange 2 of this strip has punched lugs 3 formed in the vicinity of its free edge for snappily engaging the free edge of the upper flange 4 of said cross member 5; the free edge 31 of the lower flange 6 of strip 1 is bent upwards at right angles to its plane so as to engage the free edge of the lower flange 7 of said cross member 5; thus, the strip 1 is locked on cross member 5 by the lugs 3 and the bent portion of its lower flange, as shown in FIG. 3.

To permit the engagement of the lower flange 6 of this strip under the cross member 5, the former is formed with notches 6a at either end, the width of each notch corresponding substantially to the thickness of the vertical side posts of the front frame of the cabinet.

When the strip 1 is anchored on the cross member 5 it projects from the cabinet front face by a distance corresponding substantially to the thickness of the doors and

2

door hinges, so as to constitute the element of a fillistered casing for these doors.

As shown in the figures, the hinge of each door is shifted outwardly from the main plane of the relevant door to permit an angular movement of about 270° of the door; thus, in the fully open position each door can engage the corresponding side post of the cabinet and free its front face completely.

The lower flange 6 of strip 1 has a hole 32 formed in the vicinity of its outer edge and overlying this hole is a welded inverted cup 8 constituting the female element of the door hinge.

Each door has secured along its vertical outer edge a channel section 9 having a half-round bottom, this section protruding from the front face of the cabinet by a length corresponding substantially to the thickness of the side posts of the cabinet.

Fitted in the upper end of section 9 is a bushing 10 formed with a top flange 11 bearing on the upper end of this section. This bushing 10 is also formed with an axial bore 12 adapted to receive the male element 13 of the door hinge. This male element has a lower extension in the form of a rod 14 bent at right angles, the outer, horizontal portion 15 of this rod extending rearwardly and cooperating with a lock plate 16 secured on the door liner; to this end, this lock plate 16 has a U-shaped aperture formed therein (FIG. 5), the vertical base 17 of this aperture being narrow enough to prevent the sliding engagement of said bent portion 15 therein, and having a length corresponding to the stroke of the male element 13 from its retracted position to its engaged position in the female element 8; the two horizontal portions 19 of this aperture form therebetween a locking lug 20 the purpose of which will be explained presently; on the other hand, the width of each horizontal portion 19 permits the free sliding movement of rod 15.

The lower flange 6 of strip 1 is provided as usual with a door stop 22 and formed with notches 21 adapted to be engaged by the door espagnolette bolt.

The free edge of the lower flange 6 of strip 1 is also provided preferably with a plurality of notches 18 to facilitate the removal of this strip if desired, by inserting therein a screwdriver or other similar tool acting as a lever.

The lower strip is exactly similar to the upper strip, except that it is mounted upside down, that is, with its lower flange identical with the upper flange of the upper strip; preferably, the male element 23 of the lower door hinge is molded integrally with the lower bushing 24; otherwise, this bushing 24 is exactly similar to the upper bushing 10.

Small plates 26 are secured on the ends of each strip 1 for occluding the section thereof which protrudes from the front face of the cabinet.

The method of assembling this structure is clearly shown in the exploded view of FIG. 2.

Firstly, the upper strip 1 is fitted in position by anchoring its lower flange 6 on the lower flange of the upper cross member 5 of the cabinet, then this upper strip 1 is pushed home backwards until the punched lugs 3 on its upper flange are snapped in position for locking engagement with the free or inner edge of the upper flange 4 of said cross member; the lower strip is then fitted exactly in the same manner.

The male element 23 of the lower door hinge is subsequently fitted into the corresponding female element 8, care being taken that the male element of the upper door hinge is properly retracted; the locking lug 20 of the upper door hinge is open to permit the upward sliding movement of rod 15, thus causing the male element 23 to engage the relevant female element; finally, the lug

20 is closed, thus locking said element 23 in its operative position.

Both bushings 10 and 24 are preferably made by molding from anti-friction material, and the cups 8 of the female element of each door hinge may be provided with sockets 25 of same material.

Advantageously, the doors of this collapsible cabinet may be lined with any desired and suitable material to impart a more pleasant appearance to the cabinet, but in this case, it is difficult to line also the channel members 9 of the doors as described hereinabove and illustrated in the drawings.

According to another feature characterizing this invention, these channel members 9 may be covered by a suitably shaped beading adapted to conceal the vertical edge of the door lining.

To this end, this beading 27 has a cross-sectional configuration corresponding substantially to that of channel member 9, and its outer flange is bent twice at right angles inwardly, its free edge 28 being adapted to engage a vertical slot 29 formed to this end in the door.

FIGURE 6 illustrates the fitting of this beading, which is simply threaded on the aforesaid channel member 9.

Although the present invention has been described in conjunction with a preferred embodiment, it is to be understood that modifications and variations may be resorted to without departing from the spirit and scope of the invention, as those skilled in the art will readily understand. Such modifications and variations are considered to be within the purview and scope of the invention and appended claims.

What I claim is:

1. Collapsible metal cabinet consisting of assembled frames each comprising vertical posts and horizontal cross members, said posts and cross members consisting of section elements adapted to interfit by frictional engagement, a pair of strips secured on the upper and lower cross members of the front frame, each strip having a U-shaped cross section and such dimensions as to correspond exactly in shape to the relevant cross member, one flange of each strip having its free edge bent at right angles inwardly of the frame for anchoring the strip on the free edge of the corresponding flange of the cross member of the cabinet, the other flange of said strip having lugs punched in the vicinity of its free edge for snapping into locking engagement with the free edge of the other flange of said cross member, door hinges having a female element consisting of apertures formed in said strips, channel sections fitted along the outer edges of each door, a bushing fitted in said channel section and molded integrally with the male element of the door hinge.

2. Collapsible metal cabinet consisting of assembled frames each comprising vertical posts and horizontal cross members, said posts and cross members consisting of section elements adapted to interfit by frictional engagement, a pair of strips secured on the upper and lower cross members of the front frame, each strip having a U-shaped cross section and such dimensions as to correspond exactly in shape to the relevant cross member, one flange of each strip having its free edge bent at right angles inwardly of the frame for anchoring the strip on the free edge of the corresponding flange of the cross member of the cabinet, the other flange of said strip having lugs punched in the vicinity of its free edge for snapping into locking engagement with the free edge of the other flange of said cross member, door hinges having a female element consisting of apertures formed in said strips, channel sections fitted along the outer edges of each door, a bushing fitted in said channel section and formed with an axial bore slidably engaged by the male element of the door hinge, a rod-like lower extension of said bushing which is bent inwards at right angles, and a lock plate secured on the door liner and adapted to cooperate with said bent rod.

3. In a collapsible metal cabinet having a frame structure comprising two frames consisting of vertical upright sections and horizontal transverse sections assembled by resilient mutual engagement, and doors having section elements along their edges and mounted by means of hinge pintles on the corners of the front frame, and lateral and bottom panels, a pair of get-up strips secured respectively on the upper and lower transverse sections of the front frame, each get-up strip consisting of a U-sectioned element of a length corresponding to the frame width, of a height permitting of straddling said transverse sections and of a depth exceeding the frame depth by a distance corresponding to the thickness of the door and their hinge pintles, one of the wings of said element having punched therein in the vicinity of its free edge projections capable of engaging elastically from behind said free edge the inner wing of said transverse section so as to be retained thereby, the other wing of said element being bent inwards at right angles along its edge so as to engage and be retained by the rear free edge of the other wing of said transverse section, said U-sectioned strip having formed at either ends on the one hand a notch permitting the passage of the corresponding end of the frame upright and on the other hand an aperture, a cap fitting over said aperture and constituting the female hinge element receiving said pintle.

4. In a collapsible metal cabinet having a frame structure comprising two frames consisting of vertical upright sections and horizontal transverse sections assembled by resilient mutual engagement, and doors having section elements along their edges and mounted by means of hinge pintles on the corners of the front frame, and lateral and bottom panels, a pair of get-up strips secured respectively on the upper and lower transverse sections of the front frame, each get-up strip consisting of a U-sectioned element of a length corresponding to the frame width, of a height permitting of straddling said transverse sections and of a depth exceeding the frame depth by a distance corresponding to the thickness of the door and their hinge pintles, one of the wings of said element having punched therein in the vicinity of its free edge projections capable of engaging elastically from behind said free edge the inner wing of said transverse section so as to be retained thereby, the other wing of said element being bent inwards at right angles along its edge so as to engage and be retained by the rear free edge of the other wing of said transverse section, said U-sectioned strip having formed at either ends on the one hand a notch permitting the passage of the corresponding end of the frame upright and, on the other hand, an aperture, a cap fitting over said aperture and constituting the female hinge element receiving said pintle, a socket rigid with each end of the section lining the door on the side of its hinged connection with the cabinet, a hinge pintle secured in said socket and means for retracting said pintle to permit its insertion in the corresponding female hinge element of said strip.
